GUN MUZZLE PROTECTOR

Albert G. Lampe, Madison, Wis.

Application February 2, 1950, Serial No. 141,973

1 Claim. (Cl. 42—1)

1

This invention relates to improvements in attachments for firearms.

An object of this invention is to protect the rifling in a gun barrel adjacent the outer end thereof by preventing the portion of the gun cleaning rod intermediate its ends from engagement with the rifling of the barrel during cleaning operations, as the cleaning rod is reciprocated and/or twisted.

Other objects and features will become apparent in following the illustrations.

In the drawings:

Figure 1 is a fragmentary elevational view of the outer end of a gun barrel, portions being broken away in section to illustrate detail of the attachment on the gun barrel;

Figure 2 is a side view of a fragmentary part of a gun barrel with the attachment applied at the end thereof;

Figure 3 is an end view taken substantially along the plane of line 3—3 in Figure 2;

Figure 4 is a sectional view taken substantially on the line 4—4 of Figure 2; and

Figure 5 is an exploded perspective view of the elements which form the attachment.

In cleaning a gun barrel, it is the usual practice to reciprocate a ramrod or cleaning rod in the bore of the barrel, said rod having a wadding at the end thereof. Periodic cleaning is necessary in order to maintain the firearm in proper condition.

During the cleaning operations, it is not infrequent that the rod, intermediate its ends, engages the inside surface of the barrel and it is not uncommon that this engagement causes injury to the rifling at the very end of the barrel.

The instant attachment prevents this contact of the rod with the rifling of the barrel.

The outer end portion of a gun barrel 10 is illustrated in the drawings and has a part of the conventional structure a gun sight element 12 rising from the upper surface thereof. The rifling 14 in the barrel is purely conventional in nature and typical of certain types of firearms which rely on the twist of the projectile to direct it accurately.

The attachment consists of a clamp 16 which is substantially C-shaped and is adapted to extend around only a portion of the gun barrel. The outer ends 18 and 20 of the clamp 16 are spaced from each other in order to form a passageway which accommodates or provides for the gun sight element 12. Therefore, the clamp may be placed on the outer end of the barrel

2 without interference caused by the presence of the element 12.

Means for releasably fastening the clamp in place on the outer end of the gun barrel is provided. The illustrated means consists of a screw 24 which has a knurled head and which is disposed in the thickened end portion 18 of the clamp 16. The screw is passed through an internally threaded passageway and is adapted to contact the outside surface of the end of the barrel 10.

A pair of spaced threaded openings 26 and 28, respectively, are provided in one face of the clamp 16. Screws 30 and 32 are disposed in the openings 26 and 28 after passing through slots 34 and 36 which are formed in the collar 38.

The collar 38 rests against the outside surface of the clamp 16 and is adapted to overlie a part of the end of the gun barrel 10. This collar has an opening 40 with a lip 42 rising from the collar and disposed around said opening. The opening 40, lip 42, and collar 38 form a guide for the cleaning rod, preventing it from coming into contact with the rifling of the barrel after the cleaning rod has been inserted through the open end of said barrel. The screws 30 and 32 in the openings 28 and 26, after passing through the slots 34 and 36, are used to adjustably fasten the guide to the clamp.

Reference to Figure 4 shows that there are two outwardly diverging surfaces 50 and 51 on the inside of two legs of the clamp which engage the outside surface of the gun barrel. These contact surfaces, taken together with the end of screw 24, form the friction clamping assembly for holding the device in place on the end of the gun barrel. Sufficient clearance (see Figure 4) is supplied between the surface 52 and the barrel so that the device may be used on gun barrels having different thicknesses and widths.

The barrel contacting surfaces 50 and 51 and the inner end of the screw 24 may be provided with a cover, for example, rubber, felt or other fabric, to prevent the possibility of abrasive action of the contacting surfaces on the gun barrel.

Having described the invention, what is claimed as new is:

For use with the barrel of a gun which is provided with rifling in its bore, the improvement comprising a clamp adapted to be fastened at the end of the barrel, a cleaning rod guide which includes a collar with an opening substantially the same diameter as the bore, a fastening element securing said collar to the outer face of said clamp to thereby mount said guide at the

outer end of the bore when the clamp is fastened to the barrel, said clamp having spaced portions provided with surfaces which are spaced from each other and which are parallel, the surfaces being adapted to contact opposite sides of the barrel, adjustable means carried by one of said portions and passed through its surface for fastening said clamp to the barrel, said fastening element comprising a threaded member, said collar having a lateral flange provided with a slot, and said threaded member being located in said slot so that said collar may be adjusted with respect to said clamp.

ALBERT G. LAMPE.
